APPARATUS FOR CALIBRATING TIMING
DEVICES

Douglass A. Young, East Orange, N. J., assignor
to Westinghouse Electric & Manufacturing
Company, a corporation of Pennsylvania

Application October 6, 1930, Serial No. 486,687

1 Claim. (Cl. 73—51)

My invention relates to apparatus for calibrating precision instruments and has special relation to calibrating timing instruments, such as clocks and watches.

5 An object of my invention is to provide apparatus of the above mentioned character by means of which the moving parts of a watch or clock are stroboscopically compared with an object moving at a standard rate of speed.

10 Another object of my invention is to provide apparatus, as described above, in which a relatively small error in the timing of a watch may be amplified and observed on a visible indicating device.

The former practice in calibrating watches has 15 been to set the watch according to a standardized chronometer and to observe, at frequent intervals, the difference in time recorded by the two instruments. The watch mechanism must be calibrated at all of these intervals until its time recordation approximates that of the chronometer. In most instances, the minimum time consumed 20 in calibrating a watch is seven or eight days.

By the use of my invention, a watch or clock 25 may be calibrated in only one operation and in a very short space of time, usually not more than one minute.

For a better understanding of my invention, reference may be had to the following description, 30 taken in conjunction with the accompanying drawing, in which

The single figure is a schematic view of a calibrating mechanism, constructed in accordance with my invention.

Referring to the drawing, a watch mechanism 35 1, comprising a casing 2 and an adjusting dial 3, is shown. The dial face 3 is provided with the usual calibrating scale 4. A calibrating lever 5 cooperates with the scale 4 in the usual manner. A balance wheel 6 protrudes from the casing 2. 40 An opening 7 is drilled in the periphery of the balance wheel 6, for a purpose to be hereinafter more fully explained.

An incandescent lamp 8 is connected, through 45 conductors 9 and 10, to a source of power (not shown). The lamp 8 is enclosed in a casing 11. A condensing lens 12 is provided at one end of the casing 11.

A mirror 13 is placed adjacent to the watch mechanism. A photo-electric cell 14 is connected, 50 through conductors 15 and 16, to an amplifying unit 17. A neon lamp 18 is energized, through conductors 19 and 20, from the amplifying unit 17. A viewing disc 21 is fixedly secured to a shaft 22. A pinion 23 is connected or otherwise secured 55 to the shaft 22. The pinion 23 is adapted to mesh

with the gear member 24, which is keyed to a shaft 25 of a synchronous motor 26. The synchronous motor 26 is connected, through conductors 27 and 28, to a standard-frequency device 29 comprising a tuning fork and an amplifier. The frequency 60 device 29 is connected, through conductors 30 and 31, to a source of energy (not shown).

The viewing disc 21 is provided with a circular aperture 32 near its peripheral edge for a purpose 65 to be hereinafter more fully explained.

The operation of the device is as follows:

The lamp 8 is lighted, and the timing device is placed at a point where the light beam from the lamp 8 is concentrated, by means of the lens 12, to a spot on the periphery of the balance wheel 70 6. The watch mechanism 1 is then started. As the balance wheel 6 oscillates, the aperture 7 allows a beam of light from the lamp 8 to intermittently impinge upon the mirror 13. The mirror 13 reflects the intermittent flashes of light upon 75 the photo-electric cell 14. The electrical impulses set up within the photo-electric cell 14 are amplified by the amplifying unit 17 and serve to intermittently light the neon lamp 18. The synchronous motor 26 is run at a frequency determined by the standard-frequency device 29. The frequency device 29 is of a type in which the frequency is determined by a tuning fork and an amplifying device. The frequency at which the synchronous motor 26 is run is thus essentially a 80 standard of time. The viewing disc 21 is geared to the synchronous motor 26 in such manner that the speed of the viewing disc is proportional to 85 and a multiple of, the speed of the synchronous motor. 90

The neon lamp 18 is thus lighted in accordance with the speed of oscillation of the balance wheel 6 of the watch mechanism, and if the watch is perfectly timed, the aperture 32 of the viewing disc will appear to stand still, because 95 of the well known stroboscopic effect. If, however, the timing of the balance wheel 6 is slow, the aperture 32 of the viewing disc 21 will appear to rotate in one direction. In the same manner, if the timing of the balance wheel 6 is fast, 100 the aperture 32 of the viewing disc 21 will appear to rotate in the opposite direction. To correct the timing of the watch mechanism, the lever 5 is moved in the one or the other direction, along the scale 4. When the aperture 32 of the viewing disc appears to be stationary, the operator or observer will know that the oscillation of the balance wheel 6 is in synchronism with the frequency of the motor 26, which is governed by the standard of time, and that the watch is cali- 110

brated. Since the viewing disc 21 is rotated at a multiple of the speed of the synchronous motor 26, a relatively small error in the speed of oscillation of the balance wheel 6 will cause a large 5 phase displacement between the aperture 32 and viewing consecutive flashes of the neon lamp. This feature will allow a much closer calibration of the watch mechanism.

If desired, instead of perforating the rim of 10 the balance wheel 6, a piece of reflecting material may be placed on the balance wheel to periodically reflect a beam of light from the lamp 8 directly to the photo-electric cell 14, or the wheel may reflect, and a small dark spot may 15 intercept the light.

I do not wish to be restricted to the specific 20 arrangements of parts and structural details herein set forth, as it is evident that various modifications thereof will fall within the spirit 25 and scope of my invention. I desire, therefore, that only such limitations be imposed as are indicated in the appended claim.

I claim as my invention:

In a device for testing a time indicating device 80 having an oscillating balance wheel, the combination of means for testing said device comprising a source of light, a photo-electric cell, means adapted to be associated with said balance wheel and in the path of said light beam for successively illuminating said cell in accordance with the periodicity of oscillation of said balance wheel, a gas-filled lamp and means including 85 an amplifier for energizing said lamp in accordance with the impulses generated by said cell, a standard-time device comprising a source of constant frequency electromotive force and a rotatable device driven thereby at a speed which is a multiple of the periodicity of said balance wheel when it is accurately regulated; said standard-time device and gas-filled lamp being so disposed that the speed of rotation of the former and the frequency of illumination of the latter may be stroboscopically compared. 90
